UNITED STATES PATENT OFFICE.

BENJAMIN ADRIANCE AND AMOS CALLESON, OF BROOKLYN, NEW YORK;
SAID CALLESON ASSIGNOR TO SAID ADRIANCE.

CAN-HEADING MACHINE.

No. 810,245.

Specification of Letters Patent. Patented Jan. 16, 1906.

Application filed June 17, 1903, Serial No. 161,777.

To all whom it may concern:

Be it known that we, BENJAMIN ADRIANCE and AMOS CALLESON, citizens of the United States, residing in Brooklyn, in the county of Kings and State of New York, have invented certain new and useful Improvements in Can-Heading Machines; and we do hereby declare the following to be a full, clear, and exact description of the invention, such as will enable others skilled in the art to which it applies to make and use the same, reference being had to the accompanying drawings, and to letters of reference marked thereon, which form a part of this specification.

15 This invention relates to the manufacture of sheet-metal vessels, and it has reference particularly to that portion of this art which has to do with the affixing of the heads to the bodies of cans and other substantially similar metal-shaping methods.

The principal purpose of the invention is to provide a simple, practical, and compact organism wherein the affixing of the heads of cans to their bodies may be accomplished in 25 an hermetic and otherwise effective manner, be the cans circular or non-circular in shape. The object is subserved, as will be seen from that adaptation of the machine which is herein shown and described and as will be later 30 set forth in the claims, by providing a means for holding the can and head assembled in position for the forming of the seam, a shaping means, and a means for actuating the shaping means and so adapting and combining 35 them that all said parts will be disposed with their axes coincident, or approximately so, that as between the holding means and the shaping means there shall be one of them which is rotative with reference to the other, 40 so as to cause the shaping means to travel over the path where the seam is to be formed, and that as between the shaping means and its actuating means and for the purpose of deriving the actuating effect from the latter the 45 latter shall be rotative with reference to the other, so as to cause the shaping means to have movement into and out of shaping contact with the article being shaped. It should be understood that the first of the relatively rotatory movements above referred to comprehends any condition where one of the parts involved rotatively changes its position with reference to the other, as if one is stationary

while the other rotates, or one rotates at a higher speed than the other, or if one rotates 55 in one direction while the other rotates in the opposite direction, and that the second of these relatively rotary movements comprehends any condition wherein the actuating means is rotary with reference to the shaping 60 means, as if the latter rotates more slowly than or rotates in a direction the reverse of the direction of rotation of the former or is stationary. The precise nature of the operation in the adaptation particularly shown 65 and described herein is where the holding means stands stationary while the shaping means rotates around it (thus avoiding the undesirable effects that accrue where the holding means rotates, and consequently tends to 70 induce centrifugal action on the contents of the vessel being operated upon) and where the actuating means rotates in the same direction as the shaping means, but at a higher speed.

One embodiment of a machine for accomplishing the above and other objects of more or less importance and readily to be appreciated by those familiar with the art upon properly understanding the invention is fully 80 illustrated in the accompanying drawings, wherein—

Figure 1 is a view in side elevation of said machine. Fig. 2 is a front view with certain portions of the machine broken away. Fig. 85 3 is a somewhat enlarged top plan view. Fig. 4 shows, partly in side elevation and partly in section, the parts of the machine which are directly involved in the head-affixing operation. Fig. 5 is a plan view of one of certain 90 levers 3, hereinafter referred to. Fig. 6 is a plan view of one of certain levers 8, herein-after referred to. Fig. 7 is a plan view of one of certain nuts 5, hereinafter referred to. Fig. 8 shows a lever 3 and a lever 8 and certain accessories thereof, partly in side elevation and partly in section, assembled with a certain disk *w*, in which they are mounted. Figs. 9 and 10 illustrate side views of two forms of shaping-knurl, and Figs. 11 to 13 100 show in section portions of the head and body of a can in various stages of the operation through which they pass in being united. In said drawings, *w* is a pedestal from which project laterally superposed arms *b*, *c*, 105 and *d*, the two former of which are provided

with alined bearings *e*, and the latter of which being much the heaviest and disposed at the top supports the main operating parts.

In the pedestal is journaled a horizontal shaft *f*, which carries at its inner end two bevel-gears *g* *h*, its outer end carrying a loosely-arranged pulley *i*, whereby, through a belt or the like, power is taken into the machine. On the shaft is keyed a block *j*. On the shaft is also mounted a clutch mechanism of the friction type, *k*, (which it is not thought necessary to describe, since it may be of any suitable form,) whereby the said block may be operatively connected with the revolving pulley in such manner that rotation will be imparted to the shaft. To actuate the clutch, a fork *l*, engaging an annular groove in the block *j*, is provided, said fork being carried by a sliding rod *m*, which is arranged in brackets *n* on the pedestal. In the bracket *n* which is the nearer to the free end of the rod is pivoted a latch *o*, which by engaging a notch *p* in the rod holds the rod against the tension of a retractile spring *q*, which tends to throw the fork, and consequently the block, toward the pulley, in which position, it may be said, the clutch releases the pulley.

r is the starting-lever, its function being to move the rod against the tension of the spring until the clutch effects the connection of the pulley and shaft and the latch catches and holds the rod, to which latter said lever is pivotally connected.

s indicates a post formed with a flange *t* at its lower end and having its upper portion *u* reduced and secured in the arm *d* vertically by set-screws *v*. A revolute disk *w* is supported by this flanged post, its hub portion *x* being journaled on said post between its flange and the arm *d*. Fixed to this disk, as by screws *y*, is a bevel-gear *z*, which meshes with the bevel-gear *g*. To the lower end of the post is secured, as by a bolt *1*, a block *2*, which serves both as the chuck portion of the mechanism which holds the can and head assembled while undergoing the uniting operation and as a guide for certain parts, as hereinafter described.

At diametrically opposite points in the disk *w* are arranged pairs of levers. Since the structures which comprise these two pairs of levers are exactly alike, except in a certain particular hereinafter mentioned, reference will be made specifically to but one.

3 is a lever fulcrumed in the disk, its fulcrum being afforded by a boss *4*, formed integral with it and which carries a nut *5* for maintaining the lever in place. The free end of this lever carries a roller *6*, adapted to run in the groove *7* in the under face of the block *2*, said groove being the guiding portion, already referred to, of said block and being made to conform to the outline of the can, whatever that may be, (it being rectangular,

as shown in the drawings,) so that when the disk revolves the roller *6* follows a path coinciding with the outline of the can. Said lever 3 and another lever 8 are pivoted together at approximately their middle points by a bolt *9*. The free end of lever 8 is bifurcated horizontally for the reception of a removable knurl or shaping-roller 10, (see Figs. 8, 9, and 10,) while its other end carries a vertical stud 11, which projects up through an arc-shaped slot 12 in the fulcrum portion of the lever 3 and acts as a bearing at its upper end for an antifriction-roller 13.

The mechanism above described is duplicated, being marked A and B in Fig. 3. The lever 8 in mechanism A carries a knurl or shaping-roller like that shown in Fig. 9. The parts of the can being assembled as in Fig. 11, this knurl shapes their edges primarily, as in Fig. 12. The lever 8 of the mechanism B carries a knurl which while it finally "sets" the metal, as in Fig. 13, gives it some selected shape. Such a knurl appears in Fig. 10, where its acting surface is adapted to leave the roll constituting the finished joint with its top portion projected somewhat outwardly, as in said Fig. 13. Levers 8 are the ones which act as the tools for shaping the metal. Levers 3 serve simply as their supports. Levers 8 take their general direction of movement from the levers 3; but the direct actuation thereof in order to shape the metal is imparted thereto as follows: On a shoulder 14, forming a part of the disk *w*, is revolubly arranged an annulus 15, formed with peripheral cams 16 and 16' and with a bevel-gear 17, which meshes with the gear *h*. These cams coincide for a considerable portion thereof. In their coinciding portions these cams are initially more or less abruptly inclined, as at 17^a, then very slightly inclined for a considerable distance, as at 17^b, until they finally reach their highest elevations, as at 18. At 19 the periphery of cam 16 drops to an intermediate elevation, while at 20 it drops to its lowest elevation. At 20' cam 16 drops to its lowest elevation, which elevation corresponds with elevation 20 of cam 16. Against the cam 16 bears the roller 13 of lever 8 in mechanism A, while against cam 16' bears the roller 13 of lever 8 in mechanism B.

22 is a table for supporting the can, it being carried by a vertically-movable shaft 23, which is arranged in the bearings *e* and guided by an arm 24, which is adjustably secured on the shaft by a set-screw 25 and which engages a feather 26 on the pedestal. The table is elevated so as to force the can against the chuck which the block affords by a treadle 27, which is connected with the shaft 23 by a chain 28 passing over a pulley 29, journaled in a bracket 30, sustained by the arms *b* and *c*.

31 is a brake-band which is secured at one end to the pedestal and at the other end to a

lever 32, which is fulcrumed in the pedestal and pivotally connected with the rod *m*. The brake-band surrounds the disk and is normally pulled against it by the same spring *q* which controls the rod. As a support for its outermost position a link 33 may connect it with a casing 34 (shown in dotted outline in Fig. 1) for the gearing or any other suitable part.

10 Before describing the operation of the machine it should be stated that in that embodiment of the invention shown the gearing *z g h* 17 is pitched so that six revolutions imparted to disk *w* are equivalent to five revolutions 15 imparted to annulus 15.

The starting position is where the lever 8 in mechanism A, which effects the shaping of the metal, has its roller 13 bearing against the lowest elevation 20 of the cam 16, while 20 the roller 13 of the lever 8 in mechanism B engages the lowest elevation 20' of cam 16', having just left the highest elevation 18. Both knurls are therefore held retracted by the springs 21, so that upon the can being 25 placed on the table 22 with its head applied as in Fig. 11 and being raised against the chuck in block 2 by the depression of treadle 27 it will pass up in between the knurls freely.

Lever *r* is then pulled upon until it has 30 loosened the brake-band 31 on the disk *w* and moved the rod *m* far enough so that the latch catches and retains it. The consequent rotation of shaft *f* results in the rotation of the disk and the annulus 15, the former at a faster rate than the latter, as already explained. The disk thus gains on the cam, whereby the 35 roller 13 of the lever 8 of mechanism A, which does the primary bending of the metal, is caused to ride up on cam 16, forcing the 40 knurl of said lever against the work. In the position just referred to the lever 8 of said mechanism A is maintained while the disk makes three revolutions relatively to it around the can. At the fourth revolution of 45 disk *w* the aforementioned roller 13 runs down on the elevation 19 of cam 16, and the knurl of the lever which carries said roller is permitted to withdraw from the work under actuation of its spring 21. By this time the 50 roller 13 of the lever 8 of mechanism B has run up on cam 16', bringing the knurl of this lever against the work. By the time this and the next two revolutions of the disk have 55 been completed said roller 13 will have run down onto the portion 20' of the cam 16', while the other roller 13 will have run down onto the portion 20 of cam 16. Thus both knurls will be again perfectly clear of the work. Upon this the stud 11 of roller 13 of 60 mechanism B is brought into the path of the latch *o*, tripping the same, and thus permitting rod *m* to retract, so that the clutch is rendered idle and the brake-band 31 pulled against the disk, so as to at once stop the

machine, (the stud 11 of roller 13 of the other mechanism A having been prevented from effecting the same end prematurely by the intermediate elevation 19, which said roller is then engaging.)

In practice this machine is employed for simply "heading" cans already filled with their contents; but it will be understood that it is capable of uniting the heads, both top and bottom, to the can-body. Moreover, the machine is adapted as well for bending up or over a single edge as for bending up and over two edges, as in forming a lock-joint between two edges—*i. e.*, "seaming." The expression "shaping" herein used therefore comprehends the operation above indicated, whether it involves the manipulation of one or more edges.

Having thus fully described our invention, what we claim, and desire to secure by Letters Patent of the United States, is—

1. The combination of means for holding the article to be shaped, means for shaping the article, and means for actuating the shaping means, all disposed with their axes approximately coincident, said third-named 90 means being rotary with reference to said second-named means to bring the shaping means into and out of engagement with the article, and one of said first and second named means being rotary with reference to the other to cause the shaping means to travel around the article, substantially as described.

2. The combination, with means for holding the article to be shaped and means for shaping the same, said shaping means being movable rotatively around said holding means, of means, movable rotatively and concentrically with reference to the movement of said shaping means around the holding means, for actuating said shaping means to bring the same into shaping contact with said article, substantially as described.

3. The combination, with means for holding the article to be shaped, of a rotary part, a shaping-tool carried by said rotary part, and a cam engageable with said tool to actuate the same, said cam being rotary relatively to, and having its axis approximately coincident with that of, said rotary part, substantially as described.

4. The combination, with means for holding the article to be shaped, of a shaping-tool, a part carrying said tool, and a cam engageable with said tool to actuate the same, said holding means and the tool-carrying part and the cam being concentrically disposed and said cam being movable rotatively and relatively to said tool-carrying part, substantially as described.

5. The combination, with means for holding the article to be shaped, of a lever, means for guiding one end of said lever in approxi-

mate coincidence with the contour of the article being operated upon, a rotary part in which said lever is fulcrumed, a shaping-tool carried by said lever, and a cam engageable with and adapted to actuate said tool; said rotary part and said cam being concentrically disposed and the latter being revoluble relatively to the former, substantially as described.

- 10 6. The combination, with means for holding the article to be shaped, of a lever, means for guiding one end of said lever in approximate coincidence with the article being operated upon, a rotary part in which said lever is fulcrumed, a shaping-tool fulcrumed in said lever, and a cam engaging with and adapted to actuate said tool, said rotary part and said cam being concentrically disposed

and the latter being revoluble relatively to the former, substantially as described.

7. The combination, with means for holding the article to be shaped, of shaping-tools, a rotary part carrying said tools, and cams engageable with said tools to actuate the same, said rotary part and the cams being concentrically disposed and the latter rotatable relatively to the former, substantially as described.

In testimony that we claim the foregoing we have hereunto set our hands.

BENJAMIN ADRIANCE.
AMOS CALLESON.
